(57) **CLAIM**

The ornamental design for an underwater manually launched manually spearing apparatus, as shown and described.

DESCRIPTION

FIG. 1 is a top plan view of an underwater manually launched manually spearing apparatus;

FIG. 2 is a front elevational view thereof;

FIG. 3 is a bottom view thereof;

FIG. 4 is a rear elevational view thereof;

FIG. 5 is a right-side elevational view thereof, the left-side elevational view being a mirror image thereto; and,

FIG. 6 is a left-side elevational view of the underwater manually launched manually spearing apparatus shown in a use configuration with environment of a spearfishing gun. The broken lines in FIGS. 1 and 4 depict portions of the underwater manually launched manually spearing apparatus that form no part of the claimed design. The broken lines in FIG. 6 depict environment that forms no part of the claim design.
